UNITED STATES PATENT OFFICE.

GEORGE WASHINGTON MOORES, OF NEW ORLEANS, LOUISIANA.

HAME-TUG BUCKLE.

SPECIFICATION forming part of Letters Patent No. 622,509, dated April 4, 1899.

Application filed May 6, 1898. Serial No. 679,969. (No model.)

To all whom it may concern:

Be it known that I, GEORGE WASHINGTON MOORES, a citizen of the United States, residing at New Orleans, in the parish of Orleans 5 and State of Louisiana, have invented a new and useful Hame-Tug Buckle, of which the following is a specification.

This invention has relation to hame-tug buckles, the purpose being to devise a buckle 10 which can be readily applied to a hame and which will admit of the end portion of the tug lying flat and which when in service will distribute the strain in such a manner as to withstand the pulling force without rupture or 15 breakage.

For a full understanding of the merits and advantages of the invention reference is to be had, to the accompanying drawings and the following description.

20 The improvement is susceptible of various changes in the form, proportion, and the minor details of construction without departing from the principle or sacrificing any of the advantages thereof, and to a full disclosure of 25 the invention an adaptation thereof is shown in the accompanying drawings, in which—

Figure 1 is a perspective view showing the hame-tug buckle in operative relation. Fig. 2 is a longitudinal section of the buckle. Fig. 30 3 is a side elevation of the tongue. Fig. 4 is a plan view of the buckle-frame.

Corresponding and like parts are referred to in the following description and indicated in the views of the drawings by the same reference characters.

35 The buckle-frame is of oblong form and comprises side bars 1, an end bar 2, an intermediate divided bail or billet-loop 3, and cross-bars 4 and 5, the latter being intermediate of 40 the end bar 2 and the divided loop 3 and the cross-bar 4 intermediate of the opposite end of the buckle-frame and the part 3. The side bars 1 converge toward the end remote from the end bar 2 and are united by a cross-piece 45 5^a, having a notch 6 in its outer side. The tongue 7 is mounted upon the cross-bar 4 and operates through the divided loop 3 and engages with the cross-bar 5 and end bar 2. The tongue 7 is formed with a wing or extension 50 8, which is adapted to be bent around the cross-bar 4 and form the pivotal or hinge connection between the tongue and said cross-

bar. The tongue is extended beyond its hinge connection with the cross-bar 4 and is bent to provide a hook 9, which is adapted to engage 55 with the iron or staple projecting from the hame. A shoulder 10 is formed adjacent to the extremity of the hook 9 and is adapted to engage with the inner side of the cross-piece 5^a and supplement the action of the connection 60 between the tongue and the cross-bar 4 in sustaining the pulling force, thereby materially strengthening the buckle. The shoulder 10 is depressed, forming a seat to receive the cross-piece 5^a, the connection between the 65 tongue and the cross-bar 4 being sufficiently loose to permit of the tongue having a slight longitudinal movement, so as to permit the shoulder 10 clearing the cross-piece 5^a when turning the tongue to apply or remove the 70 hame tug or trace 11 therefrom.

The space between the shoulder 10 and the terminal of the bill of the hook 9 is normally closed by the side walls forming the notch 6, the latter providing for the operation of the 75 tongue when turning it upon the cross-bar 4. The extremity of the hook 9 passes through the notch 6 when moving the free end of the tongue 7 away from the cross-bar 2 of the buckle-frame. When the buckle is in service, 80 the strain upon the hook portion 9 of the tongue holds the shoulder 10 against the inner side of the cross-piece 5^a, thereby preventing the free end of the tongue from moving away from the cross-bar 2 even though 85 the end portion of the tug is not thrust through the loop 3. An additional securing means is provided for holding the free end of the tongue against the cross-bar 2 when the end portion of the tug is slipped through the loop 3 over 90 the tongue, as indicated in Fig. 1. It will be observed that the free end portion of the tongue engages with the cross-bar 5 and end bar 2, said cross-bar serving to brace the end portion of the tongue and prevent it giving 95 way under abnormal strain.

Having thus described the invention, what is claimed and desired to be secured by Letters Patent, is—

1. In a buckle, a frame, in combination with 100 a tongue having pivotal connection with the frame, and having an offstanding part to engage with the inner side of the proximal end frame-bar, and having the end portion ex-

tended beyond the offstanding part and frame, and bent to form a hook, substantially as and for the purpose specified.

2. In a buckle, the combination with the frame having an end portion notched in its outer side, of a tongue hinged between its ends to the frame and having an end portion bent to form a hook which is normally closed by the walls bordering upon the notched end 10 bar of the frame, substantially as set forth.

3. In a buckle, the combination with the frame, of a tongue pivotally connected with the frame a short distance from an end thereof, and having a shouldered portion to engage 15 with the inner side of the adjacent end frame-bar, substantially as and for the purpose set forth.

4. The combination with a buckle-frame, of a tongue having pivotal connection between 20 its ends with the buckle-frame and having an end portion extended forming a hook and provided with a shoulder intermediate of the hook and pivotal connection between the tongue and frame to engage with the inner side of 25 the adjacent end frame-bar, substantially as set forth.

5. The combination with a buckle-frame having a cross-bar near one end, of a tongue pivotally and loosely connected with said

cross-bar to admit of the tongue having a limited longitudinal movement, and having an end portion extended and bent to form a hook, and having a shoulder intermediate of the hook and pivotal connection between the tongue and frame, said shoulder being depressed to form a seat to receive the inner side of the end bar adjacent to the hook, substantially as set forth. 30 35

6. The herein-described hame-tug buckle, comprising an oblong frame having intermediate cross-bars and an end cross-piece notched in its outer side, and a tongue pivotally connected with the cross-bar adjacent to the notched cross-piece and having an end portion extended and bent to form a hook 40 which is normally closed by the side walls forming the notch of the cross-piece, and having a shoulder intermediate of the hook and pivotal connection between the tongue and frame, substantially as set forth. 45 50

In testimony that I claim the foregoing as my own I have hereto affixed my signature in the presence of two witnesses.

GEORGE WASHINGTON MOORES.
